BICYCLE MOUNTABLE RACK FOR TENNIS EQUIPMENT OR THE LIKE

Thomas F. O'Connor, Fairway, Kans., assignor to Acme Products Co., Inc., Kansas City, Mo.

Filed Oct. 31, 1975, Ser. No. 627,709

Term of patent 14 years

Int. Cl. D12—11

U.S. Cl. D12—158

Fig. 1.

Fig. 2.

Fig. 3.

Fig. 5.

Fig. 4.

FIG. 1 is a side elevational view of a bicycle mountable rack for tennis equipment or the like showing my new design, with the bicycle being fragmentarily shown in dotted lines for purposes of illustration;

FIG. 2 is a top plan view thereof;

FIG. 3 is an end elevational view thereof;

FIG. 4 is an end elevational view thereof opposite to that shown in FIG. 3; and

FIG. 5 is a bottom plan view thereof.

The downwardly extending supporting rods have been broken away in the center for convenience of illustration in FIGS. 3 and 4.

I claim:

The ornamental design for a bicycle mountable rack for tennis equipment or the like, as shown and described.
